[57] CLAIM

The ornamental design for a square concrete bollard luminaire, as shown and described.

DESCRIPTION

FIG. 1 is a side elevation view of a square concrete bollard luminaire, the other three sides being identical to that shown;

FIG. 2 is a top view; and,

FIG. 3 is a perspective view.

The luminaire is square and thus respective FIGS. 1 and 3 show the complete or top grill design. The bottom (not shown) of the luminaire does not constitute an integral part of the disclosed and claimed design.
